United States Patent Office

Des. 228,213
Patented Aug. 28, 1973

228,213

DISPLAY STAND

Charles James Johnston, 1 Killiney Terrace, Brefnni Road,
Sandycove, Ireland

Filed May 3, 1971, Ser. No. 140,015

Claims priority, application Ireland, Nov. 4, 1970

Term of patent 14 years

Int. Cl. D6—04

U.S. Cl. D6—24

FIG. 4

FIG. 1 is a perspective view of a display stand, showing my new design;

FIG. 2 is a slightly enlarged-scale top plan view;

FIG. 3 is a bottom plan view; and

FIG. 4 is a side elevational view.

I claim:

The ornamental design for a display stand, substantially as shown.
